ART OF FEEDING AND ORIENTING SEWING HOLE BUTTONS AND MACHINE THEREFOR

William A. Troll, Brooklyn, N. Y., assignor to
Emsig Manufacturing Company, New York,
N. Y., a partnership

Application June 7, 1950, Serial No. 166,754

30 Claims. (Cl. 112—113)

1

This invention relates to button sewing machine attachments and more particularly to a button feed guide for a button sewing machine, to automatically feed buttons to the button sewing machine.

This application is a continuation-in-part of my application, Serial No. 52,682, October 4, 1948, now abandoned.

It is an object of my invention to associate with a button sewing machine, a button feed for sewing-hole buttons whereby buttons are fed from bulk supply, such as a hopper, along a chute to the presser foot of a button sewing machine, and in the course of the feed to the presser foot, the buttons are oriented accurately to position the sewing holes with regard to the path of the needle as the button holding clamp moves relatively to the needle.

More specifically it is contemplated by my invention to provide a fully automatic feed of buttons from a bulk supply, such as a hopper, to the work holding clamp of a button sewing machine whereby the presser foot manipulation of the work holding clamp to apply the work in position for sewing, followed by the opening of the work holding clamp after sewing, will serve to perform a cycle comprising ejecting a button, feeding and orienting the button and positioning the button in the oriented position adjacent the needle.

More specifically it is an object of my invention to provide a fully automatic feed for a button sewing machine including treadle control of the work clamp which will assure full cycle operation to require minimum attention by the operator and prevent failure of proper operation which may impair the rapid execution of the button sewing steps.

To attain these objects and such further objects as may appear herein, or be hereinafter pointed out, I make reference to the accompanying drawing forming a part hereof, in which—

Figure 1 is a side elevation showing my installation;

Figure 1A is a wiring diagram for the electrical connection;

Figure 2 is a magnified fragmentary view of the clamp actuating mechanism;

Figure 3 is a section on line 3—3 of Figure 2;

Figure 4 is a section on line 4—4 of Figure 2;

Figure 5 is a side elevation of the button feeding mechanism in clamping position;

Figure 6 is a similar view with the feeding mechanism raised for ejection of the sewn button;

Figure 17 is a fragmentary section taken on the line 17—17 of Figure 12.

25 In accordance with my invention, the force and movement of the lifting bar serves to actuate the work holding clamp and button feed mechanism to eject a sewn button and to orient and feed the buttons in the chute or guide from an indiscriminately arranged position to a position where the sewing holes are oriented so that the lateral jogging movement imparted to the work and button holder will position the sewing holes accurately with regard to the rectilinearly reciprocating needle.

30 The invention will be understood by reference to the accompanying drawings in which the machine frame is constructed with the usual bed plate 1, from which rises the overhanging bracket arm 2, having journaled therein a main shaft 3, to which is operatively connected the rectilinear reciprocating needle bar 4, carrying the needle 5, which constitutes one member of the stitch forming mechanism.

35 Slidably mounted upon the bed plate is a slide bar 6, constituting a carrier for the work holding parts. It will be understood that the usual arrangement is made for operation of the slide bar by a stud pin which is adjustably secured by suitable means to a crank arm of a short rock-shaft journaled in a suitable bearing in the bracket, rising from the bed plate and then carried to a roller stud entering a cam grooved in one face of a cam wheel, thus to impart end-wise movement to the slide bar. The slide bar 6 40 is fitted with clamping means for the clamp

arm 7, whose end extends in the direction of the needle and is apertured by a longitudinal slot to receive the shanks of the screws 8 tapped into the clamp arm.

The clamp arm carries the post 9, whose cross bar 10 is arranged to be engaged by the usually provided rearwardly extending bracket arm 11, mounted upon the lifting bar 12 slidably mounted within the head of the bracket arm 2, previously mentioned. The lifting bar 12, at its upper end, is provided with a collar 13, arranged to be operated by the usual clamp operating rock lever, fulcrumed upon the bracket arm 2, to be operated by the usual foot treadle chain pull before and after the button sewing operation. The clamp arm 7 is arranged to have attached to it the bracket 14, and held thereto by the screws 8 at one end 15. An extension arm 16 carries at approximately 45° thereto, a work feed chute 17 by the fastening screws 18, threadedly engaging the chute and clamping the same to the branch 16.

The chute 17 constitutes a plurality of articulated segments 19, 20, 21. The segment 21 leads to a hopper 22 which is pivotally mounted on the shaft 23 carried by the vertical arm 24, whose base 25 is mounted for swivelling movement on the standard 26 of the base 27, arranged to be attached to the table top of the sewing machine. Motor driven means 28 through the belt 29 drive a sorting mechanism within the hopper, to direct a button edgewise oriented, adjacent the port 30, which is aligned with the end 31 of the chute segment 21 to deliver to the chute segment 21 edgewise arranged buttons.

Each of the segments 18, 20 and 21 is grooved with slots 32, comprising a rectangular section enclosing the buttons to be employed. The slotted button receiving portions of each of the segments are aligned and connected by the articulated joint 33a, flexibly stiffened by a flexible shim 33, employing cover plates 34, 34, defining a slot 35 running longitudinally of the chute assembly through which the buttons B may be visible, and for purposes which will appear more clearly as this description proceeds.

The details of the motorized hopper and chute are not herein claimed, it being understood however that the lowermost segment 19 of the chute being carried by the bracket 14 vibrates the hopper during the jogging movement imparted to the chute by the clamp arm 7 without any calculated effort to effect a dampening action by reason of the articulated joint 33a and the swivelling action about the standard 26.

The lowermost segment 19 of the chute terminates in a horizontally directed elbow portion 36, to clamp the fabric against the work supporting plate mounted on the slide bar 6 and cooperating therewith to give the fabric and the button and work holder the jogging action with relation to the needle.

The slot 32 adjacent the end 37 of the elbow portion 36 is formed with a cutout 38, to afford clearance for the needle and the mouth 39 is constricted to cooperate with the resiliently urged cover strips 40 and 41, serving to pinch the opposed faces of the button which may then be positioned, as will appear more clearly as this description proceeds. The spacing between the 70 cover plates 40 and 41 defines a slot 42 (see Figure 14) which is centrally positioned with regard to the side walls defining the mouth 39 and the side walls defining the slot 32 merging in said mouth 39.

The edges 43 and 44 of the cover plates 40 and 34, defining the slot 42, are spaced from each other to form a guide diametrically across a button which may be positioned in the slot 32, and centrally thereof, and for a width substantially corresponding to the sewing apertures thereof. For a two hole button B illustrated, it will be observed that the button apertures will be aligned in the slot 42. The cover plates 40, 41, which merge adjacent the mouth 39, have flared edges 45 and 46, to expose the sewing holes so that a connecting webbing is aligned with and in parallelism with the longitudinal axis of the clamp 1, to effect a sewing operation from apertures c to b by the jogging motion of the work holding clamp for a two-hole button. A four-hole button is pictured by the dotted lines a and d in which event the feeder to be used with such buttons is turned on a bracket such as 14 clockwise at an angle to sew from a to b and from c to d by two separate series of sewing motions, the apertures c and b being aligned as in the case of the two hole button.

It will be understood that the attachment provides for the retention of the position of the button in accordance with the design of the machine either for jogging a two-hole or a four-hole button, the feed of the button being aligned in the direction of the centers of a two-hole button or with the centers of the diagonally positioned sewing holes where a four-hole button is to be sewn.

The slot 42 previously defined extends axially along the chute to a point corresponding to the position of the aperture c' of the second button rearwardly from the mouth 39 and then diverges at the portion 47 in a non-central position, to define a camming edge leading from the edge 48 to the edge 44. The edge 48 extends non-axially longitudinally of the segment 19 and is positioned with relation to the underlying wall 49 of the slot 32, to correspond to the distance from the perimeter of a button to the edge of the flare of the sewing holes.

A cover strip 41 has its edge 43 in close proximity to the offset edge 50 which non-axially diverts adjacent the edge 51 which overlaps and covers the slot 32 over the buttons therein contained so that the leading end of the slot 35 adjacent the third button 52 is in a non-axial position for a distance in a passed-dead center relation to the button, for purposes which will appear hereafter.

A separate strip 53 of spring metal may be employed to define an inwardly directed latching finger 54, which will permit buttons, when forcefully projected, to pass the finger 54 downwardly but will abut the edge of the second button to irreversibly hold it from sliding.

It will be observed that the slot defined by the edges 48, 51 and 47, 50 outline a slot which has a leading edge in a passed-dead center position with regard to apertures in the button, with a trailing slot defined by the edges 43 and 44 which is axially located, and intermediate portions which extend from an axial to a non-axial position. The slots just defined encompass a locus of points which may be assumed at the apertures from a passed-dead center position at the leading edge to a dead center position at the trailing edge.

With a chute just described, there is then provided a feeder carriage 55 comprising spaced plates 56 and 57 joined by cross bars 58 and friction reduction rollers 59 engaging the sides and

edges 60 of the chute. The front portions of the plates 56 and 57 support the cross pin 61. Pivotally mounted on the cross pin 61 are levers 62 and 63. Lever 62 has a bearing aperture 64 to permit rocking as well as pivotal movement of the lever 62 on the cross pin 61. Lever 62 has its terminal end 65 provided with a single feeler pin 66 which extends into the slot defined by the edges 43, 44, 48, 51, 47 and 50, and through a button located in the slot as previously described. The shank of the feeler pin, adjacent the section which may engage the edges, just described, is cylindrical. The end, however, is pointed or formed with a round nose for purposes which will appear hereafter. The opposed end 67 of the lever 62 is connected to an extension 68, to which a coiled spring 69 is anchored normally to urge the opposed end of the feeler pin into contact with the surface of the chute adjacent the elbow portion. The opposite end of the spring 69 is affixed to a relatively fixed portion of the chute or the sewing machine head in order to urge the feeler finger resiliently into the engaging position previously described.

The lever 62 is likewise limited in its tilting movement by the cross strip 70 integral therewith. A spring 71 mounted on the member 61 provides the resilient, relatively movable action between the levers 62 and 63, by extending its end 72 into engagement with the lever 95 and its opposite end 72a anchored to the plate 56.

A set screw 73 serves to limit the lateral tiltable movement of the feeler pin lever 62 in the movement of the feeler end against the side edges 47 of the slot, as will more clearly appear hereafter.

The feeder lever 63 has an anchoring portion 74 for a spring 75, likewise tending to urge the lever to tilt the end 76 into engagement with the chute branch 36, to direct the pair of claw pins 77 in the slot defined by the edges 43, 44. The pins 77, 77 are spaced apart for a distance corresponding substantially to the sewing holes, such as c, b. The overhanging edge adjacent the feeder lever end 76 limits the ability of the claw to ride on the surface of the cover plates 34, 34, adjacent the slot 42.

The carriage 55, previously described may have supported on the cross rod 61 a trip lever 95, separate and apart from the feed lever 63. Feeder lever 62 has a rounded bearing aperture 64 which may provide pivotal as well as rocking movement on the cross rod 61. A spacer sleeve 96 supports the coiled spring 71 previously described. The feeder lever 63 is provided with a plurality of guide slots 97 which span pins 98 carried by the tripping lever 95 and the sleeve 96.

The tripping lever 95, to the opposite end of the pivot pin 61, is provided with a laterally directed flange 78 having a camming face 79 in the direction of the chute. The flange 78 projects into the path of the guide 80 comprising an L-shaped head, the opposed end of which is affixed to the chute by the fastening elements 81. The guide 80 is made of spring sheet metal, to yield to lateral deflection, caused by the cam 79 to snap beneath the guide 80 at the end of the stroke.

With the construction as described, upon pressing the usual treadle which controls the presser foot against the clamping action of the clamp plate 7, relative downward movement of the carriage 55 will result since the post 9 has its hook member 10 engaged by the bracket arm 11 mounted on the lifting bar 12. The bracket arm 75

11 is engaged by the lever 100 which has a forked or slotted end 101. The lever is pivoted on the block 102 to extend its free end 103 with its slotted portion 104 into engagement with the finger 105 on the carriage 55. Correlation of the upward movement of the post 9 with the downward movement of the carriage 55 is thereby secured in accordance with the size of the button.

In this position, the chute end 36 corresponding to a pressure foot is spaced apart from the work supporting plate, which is designed to jog along with the clamp plate 7. The fabric F to which a button is to be sewn may now be positioned beneath the nose 36 carrying the buttons. 10 The feed of the button along the chute segments is gravitationally along the slot 32, with the carriage 55 as more clearly illustrated in Figure 6.

The buttons may gravitate within the slide to the point where they encounter the spring detent 54, extending through the cover plate 34 on the front face of the chute, at a position in the space between that which may be occupied by the second and third buttons. The detent 54 frictionally restrains the gravitational fall of the button beyond the third position of buttons in the chute in an off-center position to the right of the button so as to make possible a counter-clockwise rotation of the button. In this position, the operator then releases the foot treadle.

It is to be observed that in the relatively upward movement of the chute and the relatively downward movement of the carriage 55, the flange 78 is beneath the overhanging latch member 80, directing the claw pins or feeder 77 into intimate contact with the chute 32 and raising the feeler pin 66 upwardly for a small distance since the downward movement of the chute brings into play the cross strip 70, to be engaged by the edge 72c of the tripping lever 95, tending to tilt the aforementioned end 65 away from the chute surface.

As the treadle is released, to release the chute assembly by means of the spring action of the clamp bar 7, the latch flange 78 slides in parallelism to the chute held beneath the guide 80, maintaining the lever 63 against tilting and co-ordinating the movement of the lever 62 therewith by reason of the overlap of the crosspiece 70 on the edge 72. The feeler pin 66 and claw pin 77 are thereby withdrawn from the slot in the chute into which these pins extend, as shown in dotted lines in Figure 13. Continued movement of the carriage and chute relatively to each other to the point where the presser foot extended from the chute 36 bears against the work supporting plate releases the flange 78 from its engagement (as shown in dotted lines in Figure 17) with the guide 80 under the influence of the springs 71, 75 and 69, to restore the end 76 and the claw pins 77 within the slot defined by the edges 43 and 44, as more clearly illustrated in Figure 5. The feeler pin 66 has dropped back into the slot defined by the edges 47 and 50, to position the feeler pin 66 adjacent the most rearward position of the rim of the button which has gravitated into abutment with the detent 54 in a position opposite to the feeler pin 66.

Upon again depressing the treadle to raise the end of the chute 36 relatively to the downward movement of the carriage 55, the feeler pin 66 is guided or scans over the face of the third button in the chute and in the slot 35 between the edges 47 and 50. The floating mounting of the lever 62 permits the feeler pin 66 to follow the locus of

points which would be occupied by the perforations from a passed-dead center position controlled by the edge 51 which is the leading edge in movement of the feeler pin 66. As the feeler pin scans the face of the button in its downwardly sliding and lateral floating position, the pin will drop into one of the perforations *c* or *b*, for a two hole button or *a*, *c*, *b* for a four hole button as shown in the illustration. The feeler pin then drops into these perforations to the limit of the end 65 bearing against the strip 34, and with the shank of the pin 66 against the edge 47 by reason of the off-center spring action 69 against the opposed end of the feeler lever 62 to both tilt and turn feeler lever. The combined effect is to rotate the button about itself and against the friction of the detent 54 as it is positively slid downwardly into the second position from the end of the chute. The extreme position of movement of the feeler pin 66 is reached when the chute has moved upwardly relatively to the downward movement of the carriage 55, to guide the feeler pin 66 so that it carries the button into the second position from the end of the chute, as shown in Figure 14, with the button apertures *c* and *b* axially aligned in the chute in the centrally positioned slot 42. The friction of the detent 54 and the pushing action eccentrically of the button, coupled with the engagement of the feeler pin against the camming slot walls 47 or 50 orient the button to align the sewing hole perforations axially of the chute. A pin 63a on the lever 63 rides on the convex cam 64a slightly to raise the claw end until pin 63a strikes the shoulder 65a as the limiting position of movement, as shown in Figure 6.

Another movement releasing the treadle re-establishes the position of the feeler lever 62 to that shown in Figures 12 and 13 and drops the feeder lever 63 into position where the claw pins 77 enter the aligned perforations of the button in the second position. This has established the first button in position for positive feeding action by the lever 63. The treadle is again depressed and the chute is moved upwardly relatively to the downward movement of the carriage. The feeder lever 63 then moves a button to the extreme position of the chute. The claw pin 77 also engages the sides of the cover plates, accurately retaining the button in position. The movement forces the button into the slot 39 where the more constricted passage is found and the button is frictionally gripped by cover plate sections 40 and 41 at this point.

Upon again releasing the treadle, to drop the chute end 36, the button is exposed in the slot 39 beneath the flared edges 45 and 46 and the chute has been brought into fabric clamping position. Alignment of the sewing holes with the point of entry of the needle is assured and the sewing mechanism is then brought into play by the appropriate control, to jog the button holder and work to perform the button sewing cycle of the sewing machine. When the machine has come to rest at the end of the sewing cycle, the treadle is again depressed, to raise the chute relatively to the downward movement of the carriage 55. The feeder lever 63, during the sewing operation, is in the position shown more clearly in Figures 5, 12 and 13 as the treadle action raises the chute again. The feeder claw pins 77 push the button in the second position against the button which has been sewn, to eject the sewn button and to replace it with the button in the second position as shown in Figure 75.

6 and in dotted line in Figure 13. Releasing the treadle to drop the chute against the spring tension of the clamp bar 7 completes the cycle in preparation for the next sewing operation.

5 In the use of the button feeding mechanism, I find it desirable to employ a button which has several of the following characteristics, more specifically illustrated in Figure 16, wherein the button 89 is shown within an outlining portion corresponding to the slot 32, in magnified form. It is desirable that a face 90 of the button include a cavity disposed from the rim 91 inwardly spaced from the periphery of the button. It is desirable also that the thread receiving perforations be chamfered, for reasons which will appear herein, and that the face of the cavity be smooth. It is also desirable to form the opposed face 92 of the button symmetrical with the face 90, both with regard to the rim 93 as well as the cavity 94.

20 A button having at least one face formed with a thread receiving cavity of smooth contour, with the rim forming the highest point adjacent the overhanging plates 34 contributes to a more successful movement of the feeler pin 66 to drop the feeler pin into a thread aperture, and to orient the button from a passed-dead center position at the leading edge movement of the feeler pin into an aperture which orients the button from an eccentric position to an axial position within the slot 42. The frictional restraint of the detent 54 in the diametrically opposite position further assures a turning movement.

25 The limit of the contact of the rim 93 against the back plate 19 reduces the friction of the button with respect to the back face of the chute, to facilitate the orienting action as the feeler pin 66 urges the button from the third position to the second position in the chute.

30 40 I consider the form and contour of the button on one or both faces as contributing to the operation of the feeler pin in orienting the button as it is slid from the third position where the perforations may be disaligned, to the second position where perforations are properly oriented and aligned.

45 50 55 With a change in contour of the button, such as in using a flatter faced button, greater accuracy of guidance of the feeler pin within the locus of points occupied by a button may be required, and I may point the feeler pin 66 to a finer condition as contrasted with a round nose action in order that it may scan the button within a locus of points occupied by the thread apertures in a passed-dead center position from the leading edge of the button in the chute to the trailing edge where the button is "dragged" centrally.

60 65 Accordingly, the combination of a sewing hole button in which the feeder slot is in a non-axial position to begin engagement in passed-dead center position while stabilizing the button within the chute and the dragging action are contributing factors to the successful orientation and feeding of my device.

70 It will also be observed that the bracket connection of the chute to the work clamp during the joggling action to move the button and work in relation to the reciprocating needle provides a vibratory action which is transmitted through the articulated chute segments and to the hopper, to furnish an even and unobstructed flow of the buttons from the hopper down the chute to the orienting end of the chute, so that relatively close tolerances between the button and the slot guid-

ing the same may be retained, without obstruction of the flow of buttons.

While normal manual treadle operation may be resorted to, to actuate the lifting bar 12 through the rocking lever 14b on the bracket 14a, I prefer to actuate the installation to use a single treadle 106 to start the cycle of movement for sewing a button and to put the sewing machine into operation for each cycle involving—

a—the positioning of the fabric beneath the elbow portions 36 comprising the presser foot;

b—the release of the clamp;

c—the sewing cycle with the button in position;

d—the raising of the clamp and the ejection of the sewn button for an uninterrupted throw which will move the feeder lever with the button it carries to the preferred sewing position.

To forestall an involuntary incomplete movement of the treadle and to assure an impelling or full throw of the rocking lever 14a, I attach to the end 107 of the lever 14a an extension arm 108. The normal hook 109 for manual operation need not be removed and the usual chain with which this hook is employed is disconnected.

The arm 108 has a pull pin 110 connected by the turnbuckle 111 to the armature 112 of a solenoid 113. The solenoid is supported on a cross plate 114 and is connected to a source of power by the manual switch 115. A standard 116 supports at its end 117 the tension spring 118. The opposite end of the tension spring is connected with a pin 119 on the lever 108. The extreme end 120 of the lever 108 is connected to the rod 121 which has its piston head 122 extending into the dash pot cylinder 123. The base 124 of the dash pot cylinder is supported on the plate 114 by the fastening screw 125. The base 124 is formed with cross borings 126 and 127. The boring 127, at the end 128, is open to the atmosphere. The boring 126 leads to the interior of the cylinder.

Extending into the boring 127 in a position opposite to the opening 128 there is provided a screw valve 129 whose head 130 may be used to drive the end 131 into the path of the boring 126 adjustably to open the same. A lock nut 132 serves to hold the screw valve 129 in adjusted position.

With this assembly, on closing of the switch 115 the solenoid 113 is activated, there being a microswitch 133 mounted on the bracket 133a, maintaining the circuit closed at the contact portion 134. A switch plunger 135 bears against the lever 136 to be held in the closed circuit position. The lever 136 is connected to the pull rod 137 to the crank arm 138 on the shaft 139 for actuation through the lever 140 by the pull rod 141 connected with the treadle 106. The lever 136 has an extension cam operating the belt transfer 143 to position the belt 144 from the idler pulley 145 to the power pulley 146. The belt 144 is driven by the drive pulley 147 on the motor 148.

Upon the manual operation of the switch 115 to the closed position, the solenoid 113 will be activated and draw the armature 112 into the armature cavity, pulling against the turnbuckle 111 to trip the lever 108 with an uninterrupted impelling movement, in no way in the control of the operator during movement. The piston rod 121 operating in the dash pot cylinder 123 dampens the driving force. This action brings the presser foot to the open position, as shown in Figures 6, 12 and 13. In this position the hopper

22, when filled with buttons, will cause a flow of buttons along the chute 17, as more clearly apparent from an inspection of Figure 13. As the treadle 106 is depressed, the pressure on the microswitch plunger 135 is released, to break the circuit to the solenoid and to transfer the belt from the idler pulley 145 to the driving pulley 146, releasing the armature 112 to the pull of the weaker spring 118 and dropping the presser foot and chute end 36 into engagement, setting the button sewing mechanism into operation. At the end of the sewing cycle of the button sewing machine, with its usual provision for the number of stitches, the belt transfer is returned to its normal position, to bring the lever 136 into engagement with the microswitch plunger 135 to close the solenoid circuit and pull the armature 112 into the solenoid cavity with an impelled or full throw movement. The raising of the presser foot and button feed 17 accomplishes the double action of orienting the button with its sewing holes into proper alignment by the feeler pin 66 and ejects the sewn button by means of ejecting lever pin 77 acting on the second-in-line button.

25 The presser foot 17 being held in the open position may now have inserted there-beneath the fabric F for sewing a button on a desired location. When this has been determined by the operator, the treadle 106 is depressed, to begin a new cycle 30 of operation.

The levers carrying the pins 66 and 77, respectively, are then retracted clear of the slots in the chute containing the buttons, to return the feeler pin 66 in the leading position just back of the #3 button, and to position the claw pins 77 in the sewing holes of the button in the #2 position. Operation of the treadle is effected without fatigue and beyond the control of the operator to actuate the movement of the presser foot to any 40 intermediate position, assuring a full throw of the presser foot and a predetermined, full movement of the feeder claw with its button to the properly oriented position of the sewing holes.

While I have shown and described a full throw 45 operation of the button clamp by an electrically actuated impeller solenoid, I may substantially effect the same throwing movement manually. For this purpose I have illustrated in Figure 15 an exemplification of such embodiment wherein the lever 107 has its hook 109 connected by a pull rod 149 to the tripping lever 150 mounted on the cross shaft 151. The shaft 151 has a cross arm 152. A pin 153 is subjected to the pushing force of the link 154 transmitted to it by the swinging 50 treadle arm 155 suspended from the shaft 156 on the brackets 157 on which the shaft 151 is mounted for rotation.

The pin 153 is connected by the cable 158 to the bell crank lever 159 whose free end 160 actuates the chain 161 for operating the belt transfer lever 162 as in the prior embodiment. The treadle lever 155 has a foot support pedal on which the foot of the operator may rest. A forward movement in the direction of the arrow 164 will transmit rotative movement to the shaft 151 by means of the link 154, pulling the lever 107 to raise the presser foot. This movement releases the cable 158 to bring the belt transfer to the idler position. A reverse swinging movement of the foot in the 60 direction of the arrow 165 first releases the lever 107 and then applies tension to the cable 158, to draw down the chain 161 and move the belt from the idler position to the operating position.

The swinging treadle serves to support the 70 weight of the operator's foot, eliminating fatigue,

as well as to assure operation of the device by the momentum of swinging the foot so that no intermediate holding position is assumed, avoiding false alignment of the button feeding mechanism, and in a measure eliminating the hazard of manual operation of the presser foot.

The present invention has been illustrated in connection with a two hole button and a four hole button. It will be understood however that if is applicable to a three hole button, or any buttons in which one of the apertures is eccentrically positioned with respect of the axial slot in the leading edge contact of feeler and button.

It is to be understood that while the invention has been illustrated in connection with a button feeder for button sewing machines, this device is equally suitable for feeding buttons to mount the buttons by other than a sewing machine, such as for example, a stapler, to attach the same upon a display card or sales card, for the purpose of supplying buttons to be sold in such mounted condition and therefore the term "button sewing machine" is intended to be used in its broad aspect.

Having thus described my invention and illustrated its use, what I claim as new and desire to secure by Letters Patent, is:

1. In a button sewing machine, a button feeder comprising a chute for feeding buttons from a bulk supply and including a throat portion in the chute to feed the button in an oriented position, the combination comprising a button feeler and feeder for moving the button along the chute by engagement of a face of the button eccentrically to drag the button to an axial position leaving the button free to rotate relative to the dragging means.

2. In a button sewing machine or the like, the combination comprising a button feeder, a channel-shaped guide for the buttons for guiding the buttons edgewise, said channel having a slot through which a single feeler finger projects, to engage a button along a locus of points of the button sewing holes, said feeler including shifting means to drag said button to a new position.

3. In a button sewing machine or the like, a button feeder including, in combination, a chute for guiding the buttons edgewise comprising a slotted channel including a slotted portion defined by a cover plate outlining a path generally following the locus of points of the sewing holes, and a single shiftable feeler finger for scanning a button in said channel to orient and shift the same by engagement of the sewing hole aperture.

4. In a button sewing machine or the like, the combination comprising a button feeder including a chute for guiding the buttons edgewise and comprising a slot including cover plates, the edges of which outline a guide conforming to the locus of points of the button holes and a single feeler finger projectible into said chute, engaging said guide to orient and shift the button in said chute.

5. In a button sewing machine, a button feeder comprising a guide chute for feeding buttons edgewise from a bulk supply to means for shifting the button adjacent a sewing position of the button sewing machine in an oriented position, said guiding chute comprising a channel having a cover member, an edge portion of which cover member shields said channel off-center from a leading edge of the button to at least a central portion in the trailing edge of said button, and a feeler finger shiftable longitudinally and laterally of said channel to drag the button and orient the substantially diametrically arranged sewing holes in the direction of feed of said chute.

6. In a button sewing machine, the combination which includes a button feeder comprising a presser foot, a chute connected and movable with said presser foot, a hopper for feeding said chute, said chute having a channel for endwisely directing buttons from the hopper to the presser foot, and a feeler lever shiftable upon movement of the presser foot for orienting and shifting a button toward said presser foot.

7. In an assembly for automatically feeding buttons to a sewing hole button sewing machine which includes a presser foot button holder for holding a button in sewing position, a button feeding mechanism connected with said presser foot and actuated by the movement thereof in bringing the presser foot into and out of work engaging position, a chute and guide for buttons to be sewn, edgewise to guide buttons shiftably to said feeding mechanism, said button feeding mechanism having sewing hole engaging prong means predeterminedly positioned for advancing a button toward said button holder, and friction means along said chute and guide engaging a portion of a button to one side of center thereof, said sewing hole engaging prong means in advancing a button cooperating with said friction means partially to rotate said button to bring the sewing holes thereof into a predetermined orientation for sewing.

8. In a button sewing machine, a button feeder comprising a presser foot, a chute connected with said presser foot, a hopper for feeding said chute, said chute having a channel for endwisely directing buttons from the hopper to the presser foot, and a feeler lever shiftable upon movement of the presser foot for orienting and shifting a button toward said presser foot, and a cover plate for said chute defining a slot, an edge of which is non-centrally positioned at the leading edge of said feeler, and is centrally of said chute in the trailing edge of said feeler.

9. In a button sewing machine a button feeder comprising a presser foot, a chute connected with said presser foot, a hopper for feeding said chute, said chute having a channel for endwisely directing buttons from the hopper to the presser foot, and a feeler lever shiftable upon movement of the presser foot for orienting and shifting a button toward said presser foot, and a cover plate for said chute defining a slot, an edge of which is non-centrally positioned at the leading edge of said feeler, and is centrally of said chute in the trailing edge of said feeler, and a second button shifting lever for the button first shifted having means for holding said button against rotation during its movement in the chute by said lever.

10. In a button sewing machine, a button feeder having a channel for connection to a bulk source of supply to edgewise slide a sewing hole button in said channel, a carriage on said chute including means for reciprocation relatively to said chute, a resiliently urged feeler lever having a feeler pin for engaging a perforation of a button, said feeler lever being resiliently mounted for shifting longitudinally as well as laterally of the channel, and a cover plate for said chute to guide the feeler finger from a passed-dead center position of a button in the leading edge to a central position of the channel in the trailing edge position of the button, to orient and shift the button, and means on the carriage for shifting the button first oriented, holding said button in an oriented position during shifting.

11. A button feeding device for feeding sewing hole buttons to a button affixing machine

comprising, in combination, a chute having cover plates defining a slot, a portion of which slot merges from an off-center position with respect to a button in said chute to a central position of said chute, a carriage slideable on said chute, including a pivotal lever having a rocking lateral movement, one end of which includes a feeler pin slideable in said slot, the other end of which has means connected therewith and which includes actuating means alternatively to hold said feeler finger in said off-center slot and center portion thereof during shifting and orientation of the button in one direction, and including tripping means to release said last end of said lever to permit said actuating means to withdraw said feeler finger from said slot in reverse direction whereby buttons are oriented and fed in said chute.

12. A button feeding device for feeding sewing hole buttons to a button sewing machine comprising, in combination, a chute having cover plates defining a slot, a portion of which merges from an off-center position with respect to a button in said chute to a central position of said chute, a carriage slideable on said chute including a pivotal lever having a rocking lateral movement, one end of which includes a feeler pin slideable in said slot, the other end of which has means connected therewith and which includes actuating means alternatively to hold said feeler finger in said off-center slot and center portion thereof during shifting and orientation of the button in one direction, and including tripping means to release said last end of said lever to permit said actuating means to withdraw said feeler finger from said slot in reverse direction whereby buttons are oriented and fed in said chute, and a feeder lever having feeder pins holding said button oriented in shifting the same in said chute to the affixing position and abutting a so previously positioned button to eject the same.

13. A button feeder for feeding edgewise arranged sewing hole buttons in an oriented position to a button work holder comprising, in combination, a chute having a channel, cover plates defining a slot, a portion of which is directed in a passed-dead center position of the button and merges into a slot axially of said channel, a feeler lever having a feeler pin which may enter a sewing hole perforation from a passed-dead center side with relation to the button to a central position of the chute with relation to the button and detent means to restrain the button diametrically opposite to said feeler finger whereby shifting of the button by means of said feeler lever will shift and orient the button in the chute.

14. A button feeder for feeding edgewise arranged sewing hole buttons in an oriented position to a button work holder comprising, in combination, a chute having a channel, cover plates defining a slot, a portion of which is directed in a passed-dead center position of the button and merges into a slot axially of said channel, a feeler lever having a feeler pin which may enter a sewing hole perforation from a passed-dead center side with relation to the button to a central position of the chute with relation to the button and detent means to restrain the button diametrically opposite to said feeler finger whereby shifting of the button by means of said feeler lever will shift and orient the button in the chute, and means for shifting said button to the work holder while holding the button in the oriented position aforesaid.

15. In an assembly for automatically feeding buttons to a button affixing machine, the combination which includes a button chute for feeding buttons edgewise in said chute, said chute having cover plates having edges defining a slot non-centrally in a leading edge of the direction of feed of the button merging into a central portion in the trailing edge of the direction of feed of the button, and a shiftable feeler finger guided in said slot, means for moving said feeler finger in said slot, said feeler finger having shiftable movement longitudinally and laterally of the chute to direct the feeler finger within a perforation of said button, and upon shifting movement, to orient and shift the button.

16. A button feeder for edgewise feeding sewing hole buttons in an oriented position which includes a presser foot for attachment to the button work holder spring clamp, said presser foot comprising a chute having a button clamping throat, a carriage slideable on said chute including means for holding said carriage and connecting means for said chute to move said chute upwardly while moving said carriage relatively downwardly by the stroke of movement of the chute upwardly, and orienting and shifting means mounted on the carriage for orienting and shifting the buttons edgewise toward the throat of said chute.

30. 17. A button feeder for edgewise feeding sewing hole buttons in an oriented position which includes a presser foot for attachment to the button work holder spring clamp of the button sewing machine, said presser foot comprising a chute having a button clamping throat, a carriage slideable on said chute including means for holding said carriage and connecting means for said chute to move said chute upwardly while moving said carriage relatively downwardly by the stroke of movement of the chute upwardly, and a rocking lever engaging said carriage providing motion magnifying means to shift the carriage variably with the size of the buttons with a predetermined movement of the presser foot, and orienting and shifting means mounted on the carriage for orienting and shifting the buttons edgewise toward the throat of said chute.

18. In a button sewing machine having a presser foot forming a button holder and chute means for feeding buttons from said chute to said button holder, including means for raising and lowering said presser foot connected with means for the oriented feed of said buttons to said holder by the movement of said presser foot for a predetermined distance which actuates the orienting mechanism and ejects a button from said holder, the combination therewith of presser foot lifting means, said lifting means having impelling motive power whereby a full throw movement is transmitted to the presser foot upon initiating the impelling motive power and the buttons are fed accurately by said movement and the attached button is ejected from the holder, the impelling motive power moving the presser foot from one point to the other to complete a cycle of feeding, orienting and lowering the presser foot without restraint as to stopping during such cycle.

19. In a button sewing machine having a presser foot forming a button holder and button feeding means to said holder, and including means for lifting and lowering said presser foot for the positioning of buttons from said feeding means to said holder in sewing alignment by a predetermined movement of the presser foot

from work holding position to work and button releasing and ejecting position from said holder, the combination with the presser foot lifting means, of impact means for applying impelling motive power to said lifting means whereby a full throw movement is transmitted to the presser foot and the attached button is ejected from the holder, the impelling motive power moving the presser foot from one point to the other to complete a cycle of feeding, orienting and lowering the presser foot without restraint as to stopping during such cycle.

20. In a button sewing machine having a presser foot forming a button holder and button feeding means to said holder, and including means for lifting and lowering said presser foot for the positioning of buttons from said feeding means to said holder in sewing alignment by a predetermined movement of the presser foot from work holding position to work and button releasing and ejecting position from said holder, the combination with the presser foot lifting means, of impact means for applying impelling motive power to said lifting means whereby a full throw movement is transmitted to the presser foot comprising a solenoid impelled armature having a linkage connection to said lifting means for raising the presser foot and the attached button is ejected from the holder, the solenoid impelled armature providing impelling movement to lift the presser foot from the work clamping position to the button ejecting position to complete the cycle of feeding, without restraint as to stopping during such cycle.

21. In a button sewing machine having a presser foot forming a button holder and button feeding means to said holder, and including means for raising and lowering said presser foot for the positioning of buttons from said feeding means to said holder in sewing alignment, the combination with the presser foot lifting means, of impact means for applying motive power to said lifting means whereby a full throw movement is transmitted to the presser foot comprising a solenoid impelled armature having a linkage connection to said means for raising the presser foot and including dash pot dampening means to restrainingly control the impelling movement of the solenoid impelled armature.

22. In a button sewing machine having a presser foot forming a button holder, and chute means for feeding buttons thereto from a bulk supply, the combination including means for raising and lowering the presser foot, feed means connected with said means for raising the presser foot for positioning the button to said presser foot from said chute in oriented position and a single treadle controlled impelling motive power having linkage connected to said presser foot for lifting said presser foot for a full throw movement of the button, said treadle swinging in a horizontal plane, with magnified movement to provide impelling motive power moving the presser foot from work clamping position to button ejecting position from the holder to complete a cycle of feeding, orienting and ejection of a button, without restraint as to stopping during such cycle.

23. In a button sewing machine having a presser foot comprising a button holder, the combination comprising button feeding means, button orienting means operable by a movement of the presser foot from a work clamping to a work releasing position to shift a button from said orienting means to said button holder and in-

cluding means to eject buttons in the attaching position, and presser foot lifting means comprising impelling motive power whereby full throw movement is transmitted to the presser foot and to the button feeding means to eject the button which has been attached from the holder, the impelling motive power moving the presser foot from work clamping position to the button ejecting position to complete a cycle of feeding, orienting and ejection of the button, without restraint as to stopping during such cycle.

24. In a button sewing machine having a presser foot comprising a button holder, the combination comprising button feeding means, button orienting means operable by a movement of the presser foot from a work clamping to a work releasing position to shift a button from said orienting means to said button holder and including means to eject buttons in the attaching position, and presser foot lifting means comprising impelling motive power whereby full throw movement is transmitted to the presser foot comprising a single control treadle mounted on a swinging support, said lifting means also transmitting full throw movement to the button feeding means to eject the button which has been attached to the work from the holder, the impelling motive power moving the presser foot from the work clamping position to the button ejecting position to complete a cycle of feeding, orienting and ejection of the button without restraint as to stopping during such cycle.

25. In a button sewing machine having a presser foot comprising a button holder, the combination comprising button feeding means, button orienting means operable by a movement of the presser foot from a work clamping to a work releasing position to shift a button from said orienting means to said button holder and including means to eject buttons in the attaching position, and presser foot lifting means comprising impelling motive power whereby full throw movement is transmitted to the presser foot including a single control, actuating a solenoid having an armature connected to said presser foot lifting means and to the button feeding means to eject the button which has been attached from the holder, the impelling motive power moving the presser foot from work clamping position to the button ejecting position to complete a cycle of feeding, orienting and ejection of the button, without restraint as to stopping during such cycle.

26. In a button sewing machine having a presser foot comprising a button holder, the combination comprising button feeding means, button orienting means operable by a movement of the presser foot from a work clamping to a work releasing position and presser foot lifting means comprising impelling motive power whereby full throw movement is transmitted to the presser foot including a single control, actuating a solenoid having an armature connected to said presser foot lifting means and dampening means comprising an air dash pot restraining the action of said moving armature.

27. In a sewing machine for buttons or the like having a presser foot and a work holder, and including manually controlled means for raising and lowering said presser foot for timed feeding of the workholder by said manual means, the combination therewith of presser foot lifting means comprising a solenoid having impelling motive power and connected to said presser foot lifting means whereby a full throw movement is

transmitted to the presser foot and dash pot dampening means connected with the armature of said solenoid for restraining the impelling movement of the armature of said solenoid, the impelling motive power transmitted to the presser foot moving the same from one point to the other to complete a cycle of raising, lowering and feeding of the buttons without restraint as to stopping during such cycle.

28. In the process of feeding sewing hole buttons to a button affixing machine, the steps of orienting the button perforation predeterminedly which includes the steps of shifting the button bodily against friction applied adjacent its periphery from a passed-dead center engaging position to the oriented dead center engaging position by dragging the button during shifting about one perforation as a pivotal point in relation to said peripheral friction, to shift the button bodily to a predetermined oriented position.

29. In the process of orienting sewing hole buttons in a chute for feeding the same to a button affixing mechanism, the steps which include scanning a face of the button with a button 25 feeler from a passed-dead center position of the

locus of points of the button apertures and dragging the button by one aperture in shifting the position of the button while applying friction resistance to the peripheral edge of the button substantially diametrically opposite to the side scanned.

30. In the process of feeding sewing hole buttons to a button affixing machine with the sewing holes oriented in a predetermined position, the steps which include positioning the buttons to rest on a surface, sliding the buttons along said surface along a predetermined path by engaging a wall of a hole in an eccentric position of the button on one face thereof while exerting friction substantially diametrically opposite to said position and then dragging the button on said surface along a line axially aligned with the center of the button.

WILLIAM A. TROLL.
